UNITED STATES PATENT OFFICE.

JOHN JACOB DAY, OF MONTREAL, QUEBEC, CANADA.

NON-REFILLABLE BOTTLE.

1,116,681.

Specification of Letters Patent. Patented Nov. 10, 1914.

Application filed May 19, 1913. Serial No. 768,499.

To all whom it may concern:

Be it known that I, JOHN JACOB DAY, a subject of the King of Great Britain, and resident of 963 St. Antoine street, in the city 5 and district of Montreal, Province of Quebec, in the Dominion of Canada, have invented certain new and useful Improvements in Non-Refillable Bottles; and I do hereby declare that the following is a full, 10 clear, and exact description of the same.

The invention relates to improvements in non-refillable bottles as described in the present specification and illustrated in the accompanying drawings that form part of 15 the same.

The invention consists essentially in the novel arrangement and construction of parts whereby a particular form of stopper coöperates with a particular form of valve 20 in maintaining the non-refillable properties of the bottle.

The objects of the invention are to devise a bottle in which the stopper can be inserted at a very small cost and yet be permanent 25 and not permit interference with the particular valve mechanism which prevents the refilling of the bottle, to avoid fraudulent practices such as the usage of cheap liquor in place of the more expensive kind 30 in labeled bottles, and generally to provide a cheap and efficient non-refillable bottle.

In the drawings, Figure 1 is a vertical sectional view of the neck and upper portion of the body of the bottle showing the 35 construction of the obstructing parts. Fig. 2 is a perspective detail of the body of the stopper. Fig. 3 is a perspective view of the screw closure. Fig. 4 is a perspective view of the valve. Fig. 5 is a perspective 40 view of the valve seat. Fig. 6 is a view of the bottle inverted for pouring.

Like numerals of reference indicate corresponding parts in each figure.

Referring to the drawings, 1 is the neck 45 of the bottle having the recess 2 from the inner side forming the protuberance 3, and opposite to said recess 2 the L-shaped slot 4.

5 is the casing of the stopper having the central hole 6 therethrough, the bosses 7 at 50 the upper end and the bosses 8 a short distance below the upper end and the bosses 9 a short distance above the lower end, the said bosses 8 and 9 covering the spaces between the bosses 7, thus forming circuitous passages between the casing 5 and neck 55 1. 10 is a passage through the casing 5

and in register with the recess 2. 11 is a boss on the outer wall of the casing and through which the passage 10 extends to meet the recess 2. 12 is a teat on one of the bosses 8 and adapted to fit in the L-shaped slot 4 and by a very slight movement of the stopper lock that side of the said stopper in said neck. 13 is a screw stopper preferably of glass and having the head 14 and the stem 15, said stem having the spiral groove 16 forming in the bed thereof an eccentric surface 17 in relation to the outside surface of said stem. 18 is a cork gasket encircling the stem 15 under the head 14. 19 is a locking bar preferably of wood inserted in the recess 2 through the slot 10 and projecting into the groove 16 and engaging the said eccentric surface, so that when the stem 15 is turned the locking piece 19 is driven into the recess 2, 70 where said locking piece remains permanently, the outer end of the locking piece projecting slightly into the groove 16, thus forming a guide for raising and lowering the head 14 as well as locking said stopper securely to said casing 5, and said casing 5 securely to said neck 1.

20 is an annular valve seat having the downwardly extending flange 21 and cork 85 gasket 22 surrounding said flange and abutting the under side of the seat 20, said gasket 22 extending slightly beyond the edge of said seat 20 and engaging the inner wall of the neck of the bottle below the casing. 90

23 is a valve engaging the seat 21 having a heavy stem 24, said stem being screw threaded at 25 into the valve 23 and depending through the seat 20, said stem having the radial wings 26 extending from the 95 core 27, said wings locking said valve to said seat though allowing it sufficient play to open.

The assembled valve and seat therefor are first inserted in the neck of the bottle 100 toward the lower end, and form a distinct part of the device. The stopper portion is then inserted, the wooden piece or locking bar being held in the deep part of the thread of the screw stopper, so that it will 105 in no way interfere with the entrance of the stopper casing. A very slight thrust of said casing brings the teat 12 in the horizontal section of the L-slot and also the wooden piece opposite the recess in the neck. The screw stopper is then turned 110 and the shallower part of the thread meets

the wooden piece and thrusts it into the recess in the neck where it remains permanently. In using the bottle the screw stopper is unscrewed as far as it will turn being held from removal by the projecting end of the wooden piece. The bottle is then reversed and the liquid poured out through the port ordinarily closed by the valve and through the stopper casing.

10 The parts may be changed somewhat, though the claims for novelty following will point out the scope of the invention.

What I claim is:—

15 A non-refillable bottle having an inner recess adjacent to the top of the neck and an L-shaped slot opposite, a stopper having a cylindrical casing, said casing hav-

ing bosses from the outer wall thereof suitably spaced to form circuitous passages and a passage registering with said recess, one 20 of said bosses having a seat projecting into said L-shaped slot, a stopper having a head and a stem the latter fitting into said casing and having a spiral groove with its bed eccentric to the outside surface of said stem, 25 a locking bar extending through said passage into said recess, and a valve below said stopper.

Signed at the city of Montreal, Quebec, Canada, this nineteenth day of April, 1913. 30

JOHN JACOB DAY.
